US0D1021069S

(12) United States Design Patent (10) Patent No.: US D1,021,069 S
(45) Date of Patent:  Apr. 2, 2024

(54) FACE MASK WITH ACCESS FLAP

(71) Applicant: Andrew Mackenzie Deck, Sinking Spring, PA (US)

(72) Inventor: Andrew Mackenzie Deck, Sinking Spring, PA (US)

() Term: 15 Years

(21) Appl. No.: 29/741,628

(22) Filed: Jul. 14, 2020

(51) LOC (14) Cl. 29-02

(52) U.S. Cl. D24/110.1; D29/108

Assistant Examiner — Michael Hoffman

(57) CLAIM

The ornamental design for a face mask with access flap, as shown and described.

DESCRIPTION

FIG. 1 is a top front perspective view of a face mask with access flap showing my new design;

FIG. 2 is a bottom front perspective view thereof;

FIG. 3 is a top rear perspective view thereof;

FIG. 4 is a bottom rear perspective view thereof;

FIG. 5 is a front elevated view thereof;

FIG. 6 is a rear elevated view thereof;

FIG. 7 is a top plan view thereof;

FIG. 8 is a bottom plan view thereof;

FIG. 9 is a right elevated view thereof;

FIG. 10 is a left elevated view thereof;

FIG. 11 is a top front perspective view thereof, showing the face mask with access flap in an open configuration;

FIG. 12 is a bottom front perspective view thereof, showing the face mask with access flap in the open configuration; and,

FIG. 13 is a top front perspective view thereof, showing the face mask with access flap being worn.

The broken lines showing of ear loops in FIG. 1-13 and the broken lines showing of a head in FIG. 13 are included for the purpose of showing environmental structure and form no part of the claimed design.

1 Claim, 13 Drawing Sheets
